UNITED STATES PATENT OFFICE.

PAUL R. GOLDSWORTHY, OF SAN JOSE, CALIFORNIA.

REVOLVING AIR-PLANE.

1,254,496.

Specification of Letters Patent, Patented Jan. 22, 1913.

Application filed October 10, 1917. Serial No. 195,759.

To all whom it may concern:

Be it known that I, PAUL R. GOLDSWORTHY, a citizen of the United States, residing at San Jose, in the county of Santa Clara and State of California, have invented 5 a new and useful Improvement in Revolving Air-Planes, of which the following is a specification.

This invention relates to revolving air-10 planes and its objects are

First, to prepare revolving air-planes that the same may be used for aerial navigating machines.

Second, to so construct revolving air-15 planes that will raise the machine from the ground without a run.

Third, to so construct revolving air-planes that will divert the air pressure in the path of travel, thereby bringing the head resistance of the air to a minimum.

Fourth, to so construct revolving air-planes that will retain an aerial machine at a standing point at any height required, and one that will move forward at the will of 20 the operator.

Fifth, to provide revolving air-planes that the operator may descend at any speed required.

A further object is to provide revolving 25 air-planes that will carry the pilot, power plant and controlling members, supported by the revolving air planes, one at each side of the body portion in connection with an aerial propeller which pulls the machine 30 through the air.

A still further object is to have the air pressure under the revolving air planes and the suction effect on top of the revolving planes to exert a lift greater than the weight 35 of the machine.

I attain these objects by means of the appliances illustrated in the accompanying drawings, in which

Figure 1 is a plan view of my revolving 40 air planes, parts assembled.

Fig. 2 is a side view of the same parts assembled.

Fig. 3 is a detail part sectional view showing the bracing wire rods on both sides of 45 the revolving air planes with bracket supports, upright shafts and supporting washers in place.

Fig. 4 is an enlarged detail side view showing revolving planes in part, with ad-

justable propelling blade attached to the 55 under side thereof with cam track in position for operating the same.

Fig. 5 is a plan view of one of the lifting revolving propeller blades, with operating shaft attached thereto showing cam block 60 connected to the crank end of the operating shaft.

Fig. 6 is an enlarged detail end view of the cam block, showing rollers in place.

Fig. 7 is a plan view of Fig. 6. 65

Fig. 8 is a detail side elevation of the cam track in a straight position showing hinge and operating connection.

Fig. 9 is a detail side elevation of the cam track set in cam position. 70

Fig. 10 is a plan view of the under-side of the cam track, showing operating connection and hinges in place.

In the drawings similar numerals refer to similar parts throughout the several views. 75

My invention consists of a main longitudinal frame 1 constructed in a light and durable manner from wood or any other suitable material, having an aerial rudder 2 positioned at the rear end thereof, adapted 80 to control the forward direction of the machine from left to right; horizontal tail fin 3 is shown fastened at the rear end of frame 1 in any suitable manner, to which is connected rudder 4 by hinges 5, this rudder 4 being adapted to control the upward and downward advancement of the machine. A cross-frame 1^a is shown in dotted lines in Fig. 1, this cross-frame 1^a being connected to frame 1 in any suitable manner, near the 85 outer ends of cross-frame 1^a is positioned upright shafts 6 and 7, connected to cross-frame 1^a by thrust bearings 8 and 9; at the lower end of upright shafts is fastened bevel-gears 10 connecting with bevel-gears 11 90 fastened to horizontal shafts 12, shafts 12 connecting with any gas engine 13, in any suitable manner.

Fastened to the upper ends of upright shafts 6 and 7 are metal revolving air planes 100 14 supported on shafts 6 and 7 by a plurality of metal plates 15^b and bolts 15, steady pins in shafts 6 and 7, are shown at 15^a. A plurality of wire truss rods 16 are shown on both sides of air planes 14 held in place 105 by a plurality of truss supports 17, adapted to support revolving air planes 14.

Connected to the under side of revolving

air planes 14 is a plurality of adjustable metal propelling flukes 18, held in place on the underside of revolving air planes 14 by a plurality of bearings 19 and shafts 20. Shafts 20 are made rigid to adjustable propelling flukes 18 by clamps 21 and rivets 22. At the inner end of shafts 20 are cranks 23, to which are connected roller blocks 24 by bearings 25, rollers are shown in blocks 24 at 26, and are held in place by pins 26^a. These rollers 26 are adapted to travel in cam tracks 27, and open and close one side of propelling flukes 18 against the under side of revolving air planes 14 at the will of the operator. Cam tracks 27 are made in two halves, and are connected together by hinges 28 and rivets 29. The inner edges of propelling flukes 18 have a cut away 18^a to allow flukes 18 to close against the under side of revolving air planes 14, and metal plates 15^b. Stanchions 30 are shown bolted to cross-frame 1^a near each end thereof, by bolts 31; upright shafts 6 passing up through stanchions 30 and through thrust bearings 9, which is fastened to stanchions 30 by bolts 32, and through opening 33 in cam tracks 27. Openings 34 are shown in one half of cam track 27 for the purpose of fastening cam tracks 27 to stanchions 30 by bolts 35, the other half of cam tracks 27 being operated by rods 36 connected to cam tracks 27 at 37; and to bell cranks 38 at 39; bell cranks 38 are fulcrumed at 38^a and are fastened to stanchions 30 by bolts 40, and are operated by wires 41 and springs 39^a; wires 41 leading around sheave pulleys 42 and sheave pulleys 43 to operating levers 44; these levers 44 are fulcrumed at 45 to quadrants 46, the same having notches 47 cut therein to receive levers 44; these levers 44 and quadrants 46 are placed one on each side of the operator's seat 48, and are adapted to operate propelling flukes 18, attached to the under side of revolving planes 14.

Steering wheels are shown at 49 and 50, wheel 49 connecting with shaft 51, to which wire ropes 52 are connected leading around sheave pulleys 53 and connected to rudder arm 54 on each side of rudder 2, and are adapted to guide the machine from right to left.

Steering wheel 50 being connected to shaft 55, to which wire ropes 56 are connected, the same passing over sheave pulleys 57 and leading back to rudder arm 58 on each side of rudder 4 and are adapted to guide the machine in its upward or downward flight.

A propeller is shown at 59 fastened to shaft 60, shaft 60 connecting with any gas engine 61 adapted for the purpose.

A gas tank is shown at 62 adapted to supply gas to engine 61.

A gas tank is shown at 63 adapted to supply gas to engine 13.

An observer's seat is shown at 64; wheels

are shown at 65 connected to braces 66, adapted for making landings. Braces 66 are fastened to frame 1 in any suitable manner.

The operation of my revolving air planes is as follows: Gas engines 13 and 61 are started with a slow speed, with levers 44 in an upright position which closes cam track 27 to a straight position, and closes and holds one edge of propelling flukes 18 up against the underside of revolving air planes 14, which gives the revolving air planes 14 a lifting power; these revolving air planes travel inward from the front of frame 1; the speed is now increased by the operator on engines 13, and the revolving air planes 80 commence to raise the machine; when the same is at the required height, speed is increased on engines 61 when the machine advances forward rapidly. It now becomes necessary to lessen the upward flight; the operator moves levers 44 forward to the required notches 47 in quadrant 46 which opens cam track in cam position, and as cranks 23 are connected with roller blocks 24, which travels in cam tracks 27, open and close propelling flukes 18 at each half of the turn of the revolving air planes, which lessens the upward flight by allowing the air to pass between the revolving air planes and propelling flukes 18. Should it be required to stop in mid air the speed on engines 61 is lessened; cam track 27 is closed to a straight position, by bringing levers 44 to an upright position, which closes the inner edges of propelling flukes 18 up against the under side of air planes 14 when the required speed may be kept on engines 13 to hold position taken; should the operator now wish to descend, speed on engine 13 may be reduced as to the required speed of descending. It is to be understood that cam track 27 opens propelling flukes 18 on the advancing half turn of revolving air planes 14, at A, and closes propelling flukes 18 at the forward center B, thereby giving a lifting and forward pull on propeller flukes 18. These propeller flukes 18, may be opened to any required opening by levers 44 and held in place by notches 47.

The right and left turns are made by 115 steering wheel 49 connecting with rudder 2 by rudder arm 54 and by wire ropes 52.

The ascending and descending is governed by wheel 50 attached to shaft 55, and wire ropes 56, leading back to rudder arm 58 attached to rudder 4.

Having thus described my invention, what I claim as new and desire to secure by Letters Patent, is:

1. In revolving air planes the combination 125 of a main frame, which may be made of wood or any other suitable material, having an aerial rudder, adapted to control the forward direction from left to right, a horizontal tail fin, a rudder connected to said tail 130

- fin, adapted to control the upward and downward advancement of the revolving air planes, a cross frame fastened to said main frame, upright shafts connected to said cross frame, thrust bearings through which upright shafts pass, bevel gears fastened at the lower ends of upright shafts, horizontal shafts having bevel gears at the outer ends thereof, adapted to connect with bevel gears fastened at the lower ends of upright shafts, and drive the upright shafts; metal revolving air planes fastened to upright shafts, a plurality of metal plates, adapted to support the revolving air planes, means for fastening the revolving air planes to said metal plates and to the upright shafts, as shown and described.
2. In revolving air planes the combination of a main frame, a cross frame, upright shafts positioned near the outer ends of the cross frame, metal revolving air planes fastened to the upper ends of upright shafts, a plurality of metal plates fastened to revolving air planes and to the upright shafts, adapted to support the revolving air planes, a plurality of wire truss rods, a plurality of truss rod supports, adapted to support revolving air planes. A plurality of adjustable metal propelling flukes, adapted to propel the revolving air planes upward and forward, shafts having a crank at the inner ends thereof, adapted to operate the propelling flukes; means by which the crank shafts are fastened to the propelling flukes, roller blocks, and means by which the same are connected to the crank shafts, cam tracks, and means by which the cam tracks are operated to close and open one side of the propelling flukes, as and for the purpose described.
3. In revolving air planes the combination of a main frame, a cross frame, upright shafts positioned near the outer ends of the cross frame, metal revolving air planes fastened to the upper ends of upright shafts, means by which the upright shafts are driven, propelling flukes, and means of fastening the same to the underside of the revolving air planes, means by which the propelling flukes are operated, cam tracks, and means by which the cam tracks are operated.
5. In revolving air planes the combination of a main frame, a cross frame, upright shafts, adapted to drive the revolving air planes, a plurality of wire truss rods adapted to support the revolving air planes, a plurality of truss rod supports, adapted to support the truss rods, a plurality of propelling flukes, means by which the propelling flukes are connected to the under side of the revolving air planes, a crank shaft fastened to the propelling flukes, roller blocks, to which the crank shafts are connected, cam tracks, which the roller blocks travel in, adapted to open and close one edge of the propelling flukes up against the underside of revolving air planes at predetermined periods, means by which the revolving air planes are operated, means by which the propelling flukes are operated, as shown and described.
4. In revolving air planes the combination of a main frame, a cross frame, upright shafts, adapted to drive the revolving air planes, a plurality of wire truss rods adapted to support the revolving air planes, a plurality of truss rod supports, adapted to support the truss rods, a plurality of propelling flukes, means by which the propelling flukes are connected to the under side of the revolving air planes, a crank shaft fastened to the propelling flukes, roller blocks, to which the crank shafts are connected, cam tracks, which the roller blocks travel in, adapted to open and close one edge of the propelling flukes up against the underside of revolving air planes at predetermined periods, means by which the revolving air planes are operated, means by which the propelling flukes are operated, as shown and described.
5. In revolving air planes the combination of a main frame, a cross frame, horizontal shafts connecting with gas engines, bevel gears at each outer end of said shafts, upright shafts, bevel gears at the lower ends of the upright shafts, connecting with bevel gears on horizontal shafts, adapted to operate the upright shafts, revolving air planes fastened to the upright shafts, a plurality of metal propelling flukes, attached to the under side of the revolving air planes, crank shafts fastened to the propelling flukes, roller blocks, cam tracks, in which roller blocks travel, adapted to open and close one edge of the propelling flukes against the under side of revolving air planes at predetermined periods, as shown and described.
- In testimony whereof I hereby affix my signature in the presence of two subscribing witnesses.
